Design No. 151.

C. Chinnock. Design for Clock Case Fronts.

Patented May 23rd 1854.

Fig. 1.

Fig. 2.

Fig. 3.

Des. 651

Charles Chinnock, of New York, N.Y.
Letters Patent No. 651. Dated May 23d. 1851.

The schedule referred to in these Letters Patent, and making part of the same

To all whom it may concern.

Be it known that I, Charles Chinnock, of the City, County, and State of New York, have invented a new ornamental design for clock case fronts of cast metal, and I do hereby declare that the following is a full, & exact description of the same, reference being had to the accompanying drawings forming part of this specification, in which-

Fig. 1 is a front view of my design.

Fig. 2 is a side profile of the same.

Fig. 3 is a vertical sectional profile of the same, taken through the center.

The corresponding parts are indicated by similar letters of reference in all the Figs.

The front consists of a plate cast in one piece. The central part of the plate, surrounding the openings A, for the clock face, and B, for adjusting the pendulum, is flat. The sides are formed of ornamental pilasters C, C, supported upon pedestals D, D.

The upper part is in the form of an ornamental moulded arch supporting an ornamental capping F, and being supported by the pilasters C, C.

The pedestals are ornamented on their faces with ornaments o, o, and on their outer sides with ornamental scroll tracery p, p.

The space between the pedestals has an ornamental filling composed of ornamental mouldings a, b, panel work c, c, and scroll tracery d, e, f.

The pilasters are embellished with ornaments g, h, i, i. The arch is composed of mouldings q, r, s, t. The capping consists of continuations C, C of the pilasters C, C, ornamented in front with ornaments m, m, and at the sides with scroll tracery m, m; and a filling composed of panel work u, u, and a center piece e, finished at the top with mouldings v, v, scroll tracery w, w, and caps x, x.

3

Dec. 651

The whole plate is of nearly uniform thickness as shown in the section Fig. 3, and intended to be as light as can be cast with facility, and with due regard to a proper degree of strength.

What I claim as my invention, and desire to secure by
Letters Patent, is,

The design and configuration of the clock case front, represented in the accompanying drawings, and herein fully described.
